B. M. NYCE.

Refrigerator Building.

No. 21,977.

Patented Nov. 2, 1858.

UNITED STATES PATENT OFFICE.

BENJAMIN M. NYCE, OF KINGSTON, INDIANA.

REFRIGERATOR.

Specification forming part of Letters Patent No. 21,977, dated November 2, 1858; Reissued October 23, 1860, No. 1,068; again Reissued February 24, 1874, No. 5,772.

To all whom it may concern:

Be it known that I, BENJAMIN M. NYCE, of Kingston, in the county of Decatur and State of Indiana, have invented a new and 5 useful improvement in the mode of preserving fruit and other perishable substances, which I denominate a "refrigerating and preserving house;" and I do hereby declare that the following is a full, clear, and exact 10 description thereof, reference being had to the accompanying drawings and the letters of reference marked thereon and made to form a part of this specification.

Similar letters refer to like parts of the 15 improvement.

The invention here considered has reference to the construction and arrangement of refrigerating and preserving rooms or apartments within which a desired even 20 temperature can be maintained, without material variation, and the most perfect desiccation produced, in the manner hereinafter set forth. To accomplish this purpose, I surround the entire apartment with nonconducting walls arranged with reference to an 25 ice room in the upper part thereof, and within the preserving apartments I arrange, at desirable points, deposits of quick lime for the purpose of desiccation, and produce 30 a constant circulation of the contained air by means of a rotary fan, operated by a wind wheel placed without the said apartments.

For more perfect description I will refer 35 direct to the accompanying drawings, of which—

Figure 1 is intended to represent a vertical sectional elevation of the improvement. Fig. 2 is a transverse section taken below 40 the ice floor. Fig. 3 is a transverse sectional view of the ice floor and supporting beam. Fig. 4 is a vertical section showing the peculiar construction of the supporting beams.

45 (E) (Fig. 1) represents the outer casing of the nonconducting wall, (f) is the middle wall, and (g) is the inner partition, all made as nearly air tight as possible. The compartments (C) between the outer casing (E) and the middle wall (f) I fill with chaff or other good nonconductor. Upon the inner surface of the middle wall (f) I apply a coat of plaster to render insulation more complete and perfect. The compartments 50 (D) between the middle wall and the in-

ner partition (g) are occupied by what I call dead air. The inner surface of the inner partition (g) above the ice floor (P) is rendered water tight by application of tar or other suitable substance. The ice floor (P) is constructed of zinc or other suitable material and is made with the flange (p') fully shown in (Fig. 3) to prevent water from entering, the refrigerating apartments below. 60

65 (Z) is a discharge pipe.

(O) is an adjustable transverse partition made water tight by the application of tarred cloth or other suitable material, and is operated by means of the windlass (W) 70 (Fig. 2), and the cord (k) (Fig. 1). The partition (O) will be elevated above the door (R), ice will be passed in, in sufficient quantities upon the floor (P), when the partition (O) will be lowered until it rests 75 upon the ice. Evaporation and fermentation are thus to a great extent prevented.

(Q) is a trap door in the partition (O).

(T) (Fig. 1) are transverse beams made 80 to support the ice floor (P), the construction of which is fully shown in (Fig. 4), (X) being the upper portion of the beam (T), made of iron. (v) is the second part, made of wood. (y) is the third part, and is a metallic trough, made to receive the 85 water of condensation which may collect about the upper portions of the beam (T).

(U) is the fourth and principal portion of the supporting beam (T).

(A) is the outer door to the refrigerating 90 and preserving apartments, and is made with double walls, having the compartment (G).

(B) is the inner door, and is made as 95 nearly air tight as possible, and for that purpose I use list, woolen cloths, etc., tacked to its edges.

(H) are shelves for the reception of fruit, etc.

(K) is a rotary fan made to operate by 100 means of the wind wheel (N).

(F) (Fig. 2) are receptacles for quick lime, which is deposited in any desirable number of places within preserving room for the purpose of absorbing the moisture of the air, and as the fan (K) rotates the air is circulated so that all the contained air will come in contact with the lime and thus produce the most perfect desiccation within the said apartments. 110

What I claim as my invention and desire to secure by Letters Patent is—

1. The employment of the fan (K) when arranged as set forth for producing a circulation of the contained air, so as to bring it in immediate contact with the lime or other desiccating composition for the purposes herein specially set forth.

2. I claim the peculiar construction of the beam (T)—that is to say, I claim the metal bar (x), the insulating beam (v) the

trough (y) and supporting beam (U) all arranged for the purposes and in the manner described.

3. I claim the partition (O) when arranged and operating substantially in the manner and for the purposes herein set forth.

BENJN. M. NYCE.
